(57) **CLAIM**

The ornamental design for a bald eagle ring float, as shown and described.

DESCRIPTION

FIG. 1 is a perspective view of a bald eagle ring float;
FIG. 2 is a front elevational view of the bald eagle ring float.
FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines depict surface indicia that forms no part of the claimed design.
